FIG. 1

FIG. 2

FIG. 3

FIG. 4

FIG. 5

FIG. 6

FIG. 1 is a perspective view of a watch band showing my new design; and

FIG. 2 is a plan view of one end of the watch band illustrated in FIG. 1.

FIG. 3 is a longitudinal sectional view on lines 3—3 of FIG. 2;

FIGS. 4 and 5 are transverse sectional views on lines 4—4 and 5—5 respectively of FIG. 2;

FIG. 6 is a fragmentary longitudinal section similar to FIG. 3 showing a portion of the band on an enlarged scale.

The dominant features of my design reside in the portions shown in full lines.

I claim:

The ornamental design for a watch band or the like, as shown and described.
